UNITED STATES PATENT OFFICE.

JOHN W. PIERSON, OF CLEVELAND, OHIO.

VIOLIN.

SPECIFICATION forming part of Letters Patent No. 364,291, dated June 7, 1887.

Application filed May 2, 1887. Serial No. 236,795. (No model.)

To all whom it may concern:

Be it known that I, JOHN W. PIERSON, of Cleveland, in the county of Cuyahoga and State of Ohio, have invented certain new and 5 useful Improvements in Violins, of which the following is a specification.

This invention relates to certain improvements in violins and violas; and it consists in the peculiar construction of such musical 10 instruments, as hereinafter described and claimed, whereby the tone of the instrument is greatly improved and the economy of manufacture is greatly increased. To accomplish the said results I make the neck and band of 15 the instrument entirely of one piece, thereby obtaining solidity in these parts of the instrument, whereby a clearer, steadier, and more perfect tone is produced, and whereby greater facility and cheapness in the manufacture of 20 the instrument are also obtained.

In the drawing, the figure shows the neck and band as cut in one continuous piece.

A represents the neck and B the band of a violin. These parts of the instrument I saw 25 out of one solid piece of wood in one continu-

ous piece, as shown. To this band is attached the usual top and bottom boards in completing the instrument.

Heretofore the neck and band of a violin have comprised as many as fourteen (14) different pieces, consisting of a separate neck, 30 bent pieces forming the band, and blocks glued into the corners and at the joints of the pieces, in order to strengthen and hold the pieces together, requiring much skill, time, and labor 35 to construct.

By selecting a good quality of wood and sawing the neck and band from the same in one continuous piece, as shown in the accompanying drawing, I am enabled to produce an 40 instrument of better tone and at greatly reduced cost of production.

Having described my invention, I claim—
A violin having the neck and band portion 45 integral and cut in one continuous piece, substantially as shown and described.

JOHN W. PIERSON.
